UNITED STATES PATENT OFFICE.

HENRY M. DEXTER, OF WASHINGTON, DISTRICT OF COLUMBIA.

ADVERTISING OR ORDER DESK.

SPECIFICATION forming part of Letters Patent No. 392,856, dated November 13, 1888.

Application filed September 12, 1888. Serial No. 285,195. (Model.)

To all whom it may concern:

Be it known that I, HENRY M. DEXTER, a citizen of the United States, residing in the city of Washington, in the District of Columbia, have invented a new and useful Improvement in Advertising and Order Desks, of which the following is a specification, reference being had to the accompanying drawings, forming part thereof, in which—

10 Figure 1 is a front elevation of the desk. Fig. 2 is a cross-section, and Fig. 3 is a top view thereof.

My invention, whereby a glass-covered advertising-space, card-rack, tablet-holder, and 15 locked order-box are combined in one device as an order-desk, is intended for the use and convenience of persons and firms who may desire to save the expense of agencies and advertise their business by locating the desks conspicuously at stores, hotels, and other public 20 places, where they may become the medium for the deposit and collection of business orders and messages, and also for the use and convenience of professional men, artisans, mechanics, and others who are necessarily much 25 absent from their places of business, by attaching the desks to the entrances or walls of said business places or elsewhere thereabout, thereby avoiding the undesirable features attending 30 the use of the primitive slate for such purposes.

The desk is constructed substantially as illustrated in the drawings, to wit: A desk-table, A, is mounted on bracket-supports K K, and has a back board, B, with a rounded top holding the 35 table and supports, and has a slot, G, for dropping orders into the box F, and bears a tablet-holder, E, suitably inclined, as shown in Fig. 2, with cleats e e for holding the tablet-base in

place. Back of the table A is the card-rack D, and a space, H, on the back board, B, to receive advertisements. Over this space H is a glass cover held in a metal frame, C, hinged below at c' c' for opening to insert or change the advertising-sheets. The pin or catch b serves to fasten and keep the glass cover in place. Below the table A, and between the side brackets, K K, is the order-box F, with a door opening outward and downward on hinges f' f', and provided with a lock, f, above.

Having fully described my invention, what I desire to claim and secure by Letters Patent is—

1. An advertising and order desk combining in one device a back board, B, having an advertising-space, H, a desk-table, A, a card-rack, D, at the back of the table A, below the advertising-space, an inclined tablet-holder supported on the table A, and the order-box F, located beneath the table A, substantially as and for the purpose set forth. 55

2. The combination of the table A, having the slot G and the inclined tablet-holder, brackets for supporting the table, and a hinged door, F, forming an order-box beneath the table, and a back board, B, having a glass-covered advertising-space, as set forth. 65

3. In an order-desk, the combination of a table, A, having an inclined tablet-holder, a slot through the said table, and an order-box located beneath the table, having a hinged door provided with a lock, substantially as set forth. 70

HENRY M. DEXTER.
